EDMOND KUHN, OF EAST ORANGE, NEW JERSEY, ASSIGNOR TO ERNEST BUNZL AND GUSTAV BUNZL, OF NEW YORK, N. Y.

PEDOMETER.

SPECIFICATION forming part of Letters Patent No. 770,644, dated September 20, 1904.

Application filed April 30, 1904. Serial No. 205,814. (No model.)

To all whom it may concern:

Be it known that I, EDMOND KUHN, a citizen of the United States, residing at East Orange, Essex county, State of New Jersey, have invented new and useful Improvements in Pedometers, of which the following is a specification.

By means of this invention the length of steps can be plainly shown and correct adjustment can be readily obtained by a simple construction.

This invention is set forth in the following specification and claims and illustrated in the annexed drawings, in which—

15 Figures 1 and 2 show opposite face views of a pedometer embodying this invention. Fig. 3 is a section along $\alpha\alpha$, Fig. 1. Fig. 4 is a section along yy , Fig. 2. Fig. 5 is a section along zz , Fig. 1.

20 In the drawings are shown frame-plates a^2 . The pendulum or weighted arm is shown at b , and to its staff b^2 is secured one end of the spring h . The other end of this spring is braced, as presently described. This spring 25 tends to hold the pendulum to the stop d , and as under the influence of a step or other impulse the pendulum swings away from the stop the spring will return such pendulum. The pendulum is thus oscillated as the person 30 carrying the instrument walks or causes movement. This spiral spring secured, as stated, to the pendulum-staff is also secured or braced against an arm i , pivoted at k by means of a stud or the like. This stud k may

35 extend through the opposite side or plate or be secured to only one plate or between the plates, as no limitation of the invention resides in the various arrangements. This pivot k is friction-tight, or does not move under the

40 strain or tension of the spring. If, however, the pendulum for its proper swings requires either a stronger or weaker tension, the pivot k or arm i is turned or set to accomplish the desired object or regulation of the spring according to the direction of the turn. The pivot k might, if desired, have a notch for engagement by a screw-driver or tool to aid in adjusting or setting.

The swing of the pendulum away from the

stop d is limited by adjustment-screw e . The 50 space between parts d e or the degree of swing must of course be regulated according to the length of step if the pedometer is to correctly measure or indicate a walk or distance. The screw e is supported by stud c , (shown secured to a frame-plate.) The head of the screw 55 has transverse holes, which offer convenient means for the insertion of a pin or the like to turn or set the screw. This screw head or bottom rests against an end of a lever f , 60 fulcrumed at f^2 , or rather a spring f^3 by its tension holds the lever to the screw. This lever is shown with one of its arms at one side of a frame-plate and the other arm at the other side; but of course this arrangement could be 65 changed or modified without departing from the invention.

The screw e as it is turned or adjusted will cause the lever f to swing, and as said lever moves or sweeps along a scale g the degree of 70 setting or adjusting of the screw is observed. In case the lever or an arm thereof lies under a frame-plate, as in the particular example shown, the plate has to be cut or provided with a sight or opening to allow the end of 75 the lever which forms the index or indicator part to be seen and its position or movement along the scale or slot to be noted. As seen even on a slight movement of the screw the lever following the screw and arranged as 80 shown will show by its end or by its longer arm the movement of the screw in an enlarged degree.

The lever shown might be said to be a lever of the first class; but of course by a manifest 85 transposition of parts or shift of the fulcrum this index or hand might be another lever—as, for example, of the third class and actuated by the screw in any suitable manner.

Familiar parts of the pedometer—such as 90 the pawl, spring, and ratchet connection from the pendulum to the train of gears and the like—need no explanation.

What I claim as my invention, and desire to 95 secure by Letters Patent, is—

1. A pedometer provided with a pendulum, a regulator or adjustment-screw for determining the swing of the pendulum, and an

index or hand engaged by the screw to be set thereby.

2. A pedometer having a pendulum and an index, combined with an adjustment-screw 5 one end of which serves to limit the play or swing of the pendulum and the other end of which serves to set the index.

3. A pedometer having a pendulum and an index, combined with an adjustment-screw 10 one end of which serves to limit the play or swing of the pendulum and the other end of which serves to set the index, and a spring for holding the index to the screw.

4. A pedometer comprising a pendulum, an

adjustment-screw for the pendulum, and an 15 index or indicator lever fulcrumed to a plate or part of the pedometer, said screw being made to actuate the lever so that the latter will make a sweep or swing as the screw is set or adjusted.

20 In testimony whereof I have hereunto set my hand in the presence of two subscribing witnesses.

EDMOND KUHN.
